UNITED STATES PATENT OFFICE.

FRED M. KILFOYLE, OF STORRS, UTAH,

PULLEY.

Application filed February 6, 1922. Serial No. 534,453.

To all whom it may concern:

Be it known that I, FRED M. KILFOYLE, a citizen of the United States, and a resident of Storrs, in the county of Carbon and State 5 of Utah, have invented certain new and useful Improvements in Pulleys, of which the following is a description, reference being had to the accompanying drawing, which forms a part of my specification.

10 My invention relates more particularly to a clothes line reel or pulley of such construction that an endless clothes line may be disposed about a pair of reels or pulleys arranged a suitable distance apart, to permit 15 the use of both strands or bights of the line and enable clothes to be suspended from or hung on the line at one end thereof and the line with the suspended clothes made to travel or pass about the different, separated 20 pulleys. In other words, my invention permits the clothes to be secured on the line at any suitable or selected point and the line gradually advanced a sufficient distance to permit a number of separate garments to be 25 successively suspended therefrom, without requiring the user to walk from place to place or to opposite ends of the line.

A purpose of my invention is to provide 30 pulleys which will be comparatively light in construction; which may be readily assembled and dissociated or knocked down for shipment; and which at the same time possess the necessary strength and rigidity, while at the same time of such construction 35 that it will be comparatively inexpensive in manufacture and permit of such mounting that any slack in the line may be readily taken care of and yet at the same time preventing the line from readily slipping off 40 the pulley or reel; the construction of the reel permitting the line with the clothes suspended therefrom to pass about the pulley or reel, without, however, causing general contact between the clothes and the pulleys 45 or reels.

The objects and advantages of my invention will all be more fully comprehended from the detailed description of the drawing wherein:—

50 Figure 1 illustrates, in elevation, my improved pulley or reel supported from a suitable bracket, with a portion of the line or wire shown in place.

Figure 2 is a sectional view taken on the 55 line 2—2 of Figure 1.

Figure 3 is a top plan view thereof.

Figure 4 is a perspective view of the outer hub member.

Figure 5 is a perspective view of the inner hub member.

In the particular exemplification of the invention as disclosed in the drawing, the pulley or reel comprises a hub member or shell 10 of metal or any suitable material; the opposite ends thereof being preferably 60 provided with a number of sockets 10^a for the reception of the spoke-forming wires 11, 11, the inner ends whereof are adapted to extend into and be disposed along the inner surface of the shell or hub member 10. The 65 hub member or shell 10, at an intermediate point, is provided with a series of circumferentially arranged holes 10^b, through which the immediate ends of the wires are disposed; the wires, leading from opposite 70 ends of the hub, being bent into parallel 75 relation and passed through the holes as shown at 12 in Figure 2.

The inner ends of the respective wires or 80 spokes are maintained in place by means of 85 an inner hub or member 13, which may be in the nature of a cylindrical core or shell, having its sides provided with longitudinally disposed grooves 13^a, at points registering with the holes in the outer shell or hub 90 10, adapted to receive the portions of the wires, arranged within the outer shell or hub, to maintain the wires or spokes in place. The inner hub member or shell is 95 preferably shown cored to receive a suitable bolt 14 which is secured in a suitable manner to a block or member 15. The opposite sides of the hubs are preferably provided with suitable discs or flanges 16 arranged in pairs and grooved to provide race-ways 100 95 for the ball-bearings indicated at 17; the discs being shown held in place, at one end, by the bolt-head, while the discs at the opposite or upper end of the hubs are shown held in place by the block 15. This construction will provide an easy operating 105 pulley or reel which will respond or rotate through a slight pull on the clothes line or wire.

The spokes 11, leading toward opposite 110 ends of the hubs, may each consist of a single wire of proper length to provide the size of pulley or reel desired; while the intermediate portion of each wire is bent into loop or fork-form to provide a socket or crotch for the clothes line which is indicated at 18. The spokes preferably each consist

of a single wire bent to form the loops or extensions 19 and 20; the object being to provide the diverging loops or extensions 19 and 20 whereby a suitable crotch or 5 groove is provided for the reception of the line 18. I prefer that the extension or loop on one side of the reel or pulley, namely the side which is disposed downwardly, be made of slightly greater length than the extension or loop 19 to prevent possibility of the line or wire slipping out of the crotch or groove and therefore off the reel.

The block or member 15 is preferably shown reduced or socketed on opposite sides 15 to receive channel irons 21, 21 of a supporting bracket indicated at 22 in Figure 1, which is adapted to be bolted or otherwise secured to any suitable upright or post as shown at 23 in Figure 1. The bracket 22 20 may be in the nature of a metallic loop disposed about opposite sides of the block or member 15; with the intermediate or outer portion of the bracket preferably provided with a block 24 having a tapped opening 25 for the passage of an adjusting bolt 24^a of suitable length, so that when the bolt is screwed inwardly it will force the block or member 15 toward the inner end of the bracket 22 and thereby cause the pulley or reel to be moved toward the attached end of the bracket, namely in a direction away from the pulley or reel located at the opposite end of the line; the construction enabling any slack in the line to be taken up. 30 My improved pulley is more especially intended for use in connection with clothespins of the type whereby the clothes are suspended from and beneath the line without actual contact therewith; namely the type of clothes-pin disclosed in my prior Patent No. 1,398,969, December 6th, 1921. This type of clothes-pin enables the clothes to be suspended from the line a distance sufficient to clear the downwardly disposed 45 loop or prong 20 of the respective spokes, thus enabling the line with the suspended clothes to pass about the pulleys arranged at opposite ends of the line.

My present construction permits the use of the entire line, while the user is enabled to apply the clothes to the line from a given point or same position without necessitating walking from end to end of the line to fill the entire line; and where the line is suspended at a height from the ground, it is evident that the full length of the line may be employed and therefore a greater number of garments suspended from the line and its full capacity employed; and by 55 merely presenting the prongs or forks to the line, instead of a rim or continuous periphery as in the ordinary pulley, it makes it possible for the clothes to pass about the pulley without contact therewith.

60 The construction shown and described is

comparatively light in weight, while at the same time possessing the required strength and rigidity; the spokes or wires being of any suitable non-rusting metal so as to withstand the elements and not be affected by 70 moisture. It is also apparent that the pulleys may be operated by any suitable means, if desired, although they are readily operable by hand because of lightness in construction.

In the preferred construction of my invention, the spokes are preferably each composed from a single wire; with the upper strand preferably made to extend substantially straight outward from the top end of 80 the hub, as shown in Figure 2 and bent into the loop form as previously described; the wire or spoke is then twisted so as to provide a small loop or eyelet at a point just rearward of the line-receiving crotch as 85 shown at 25. The spoke is preferably formed so as to have the lower strand of the wire extend in the downward inclining manner toward the lower end of the hub, thus causing the lower strand to act as a brace 90 for the outer end of the spoke. The small loop or eyelet 25 is intended to be just large enough to receive a tie-wire 26, which is preferably employed to reinforce and maintain the spokes in spaced relation. The 95 small loop or eyelet is arranged at a point in the spoke, rearward of the line-receiving crotch, where the tie-wire 26 will not interfere with the line and therefore not interfere with the free passage of the clothes and 100 the holding pins. I prefer to provide the tie-wire 26 with small enlargements or lugs 27 arranged in pairs and spaced sufficiently apart to receive the spoke therebetween; the enlargements being small enough, however, 105 to enable them to be forced through the small loops or eyelets when it is desired to thread the tie-wire therethrough in assembling the pulley. The ends of the tie-wire 26 are provided with a turn-buckle 28 whereby the tie-wire may be made taut. The arrangement of the spokes as shown, with the tie-wire as described, greatly increases the strength of the spokes; the tie-wire being placed under a tensile stress 110 when the outer end of the spoke receives a downward pressure; while the great angle or inclination of the lower strand of the spoke acts as a brace and therefore will sustain more strain.

As is apparent from the construction shown and described, a pulley or reel is provided which may be readily put together or assembled, while at the same time the pulley or reel may be quickly "knocked down" or taken apart upon removing the securing bolt from the inner hub member 13 and then withdrawing the inner hub member 13 from the outer hub or shell 10, which will permit the respective spokes to 115 120 125 130

be removed from the hub 10 after releasing the tie-wire. The construction enables the "knocked down" pulley or reel to be stored in a comparatively small space or packed in 5 a small carton for shipment; while at the same time enabling the parts to be easily assembled without special skill or tools.

I have shown and described what I believe to be the simplest embodiment of my 10 invention; having described the same in terms employed merely as terms of description and not as terms of limitation, as structural modifications are possible and may be made without, however, departing from the 15 spirit of my invention.

What I claim is:—

1. A pulley of the character described, comprising an outer hub member, wire spokes, bent so as to provide diverging extensions, while the ends of the spokes are bent to extend parallel with the inner perimeter of said hub member, an inner hub member adapted to fit within the first hub member, to clamp the spoke-ends in place, 20 and means disposed axially through the second hub member to permit rotation of the latter thereon, whereby the pulley may be rotatably secured in place.

2. A pulley of the character described, 30 comprising a cylindrical outer hub member, the opposite ends whereof are provided with a plurality of radially disposed sockets, spokes consisting of wires bent to provide diverging extensions at the outer ends of the 35 spokes, while the inner ends of said wires are arranged in said sockets and bent to extend parallel with the inner surface of the cylindrical hub member, a second cylindrical hub member adapted to fit within the 40 first mentioned hub member and to hold the ends of the wires in place, and means disposed axially through the second hub member to permit rotation of the latter 45 thereon and to secure the pulley in place.

3. A pulley of the character described, 50 comprising a hub, spokes radiating from said hub, each spoke consisting of a single wire bent at an intermediate point to provide diverging extensions, and a tie wire adjacent to the outer ends of the spokes rearward of said extensions, the spokes being twisted to form eyes near said extensions, 55 through which eyes the tie wire passes.

4. A pulley of the character described, 60 comprising a hub member having sockets at its opposite ends, spokes consisting of wires whose ends pass through the sockets of the hub member and extend parallel with the inner surface of the hub member, the outer ends of the spokes being formed to provide diverging extensions, with one of the extensions of each spoke being of greater length than the other, a tie-member dis-

posed about the pulley and secured to the respective spokes at points adjacent to the 65 crotch of the extensions, a second hub member adapted to fit into the first mentioned hub and provided with longitudinally extending grooves adapted to receive the ends of the spoke-wires disposed within the first 70 hub, and means disposed through the second hub member whereby the pulley may be rotatably secured in place.

5. A pulley of the character described, comprising an outer hub member, the ends 75 whereof are provided with a plurality of spaced sockets, while the intermediate portion is provided with a plurality of openings, spokes consisting of wires radiating from said hub member, the wires being disposed in said sockets and extended parallel with the inner side of the hub, with the ends being bent and disposed through said openings, while the outer ends of the spoke-wires are bent to provide diverging extensions, a second hub member adapted to fit within the first member and provided with a plurality of longitudinally disposed 80 grooves adapted to receive the portions of the spoke-wires located within the first hub 85 member and to clamp the spoke-wires in place, and means disposed through the second hub member whereby the pulley may be rotatably secured in place.

6. A pulley of the character described, 90 comprising an outer hub member, wire spokes, the inner ends whereof are arranged within said hub member, a second hub member adapted to fit within said first hub member to clamp the ends of the spoke 100 wires in place, a journal member disposed axially through the second hub member, and means on the journal member at opposite ends of the hub members whereby proper relation between the hub members is maintained.

7. A pulley of the character described, 110 comprising an outer hub provided at opposite ends with sockets, spokes consisting of wires twisted at their intermediate points to provide diverging extensions at the immediate ends of the spokes and with eyelets adjacent to the extensions of the spokes, the spoke-wires being arranged in the sockets of said hub and having their ends disposed 115 parallel with the inner surface of said hub, an inner hub, grooved to receive the ends of said spoke-wires, for clamping the wires in place, a tie-wire disposed through the eyelets of the spokes, and means for regulating 120 the tension of said tie-wire.
